UNITED STATES PATENT OFFICE.

MICHAEL J. MCINTYRE, OF BUFFALO, NEW YORK, ASSIGNOR OF ONE-HALF TO WILLIAM BRENNAN, JR., OF BUFFALO, NEW YORK.

GAME APPARATUS.

1,128,887.

Specification of Letters Patent. Patented Feb. 16, 1915.

Application filed November 2, 1914. Serial No. 869,935.

To all whom it may concern:

Be it known that I, MICHAEL J. MCINTYRE, a citizen of the United States, residing at Buffalo, in the county of Erie and 5 State of New York, have invented a new and useful Improvement in Game Apparatus, of which the following is a specification.

This invention relates to games and it consists in the novel features and combinations of parts hereinafter set forth and more particularly pointed out in the claims.

The object of the invention is to provide a game having movable portions representing animals and requiring a certain amount of manual skill to score the points of the game which are made by lassoing the animals' heads with a ring and to provide a means of indicating the points scored.

20 For a full understanding of the invention reference is to be had to the following description and accompanying drawings, in which:

Figure 1 is a front elevation of the game set up and ready to be played. Fig. 2 is a sectional elevation on the line 1—2 of Fig. 1. Fig. 3, is a sectional elevation on the line 3—4 of Fig. 4. Fig. 4 is a sectional elevation on the line 5—6 of Fig. 3. The 30 different sections are shown looking in the direction of the arrows. Figs. 3 and 4 are upper portions of the game shown complete in Figs. 1 and 2 and illustrate a modification of the game shown in Figs. 1 and 2.

35 Referring to Figs. 1 and 2 A is a box entirely inclosed and having slots through which project the animals E, E¹ and E². C is a crank shaft extending through the box A from side to side and having cranks Q, 40 Q¹ and Q² to which the animals E, E¹ and E² are attached respectively. The ends of the crank shaft C are inserted into the box A through slots in its sides and held in place by means of the staples P and P¹. One end 45 of the shaft C is turned up to hold the shaft in place and the opposite end is made square to accommodate the crank D which can be slipped on and off at will. D¹ is a handle on the crank D. The animals E, E¹ and E² 50 rest on the lower edge of the slots and when the crank C is turned they have an alternate forward and backward movement while their heads are also raised and lowered due to the rotary movement of the cranks Q, Q¹ and Q², which gives the animals the effect of

jumping. B is another box open in front and forming a base for the box A to which it is hinged by means of pieces of cloth or other flexible material O, O and O. N is a circle of numbers for indicating the score 60 by means of the pointer K. J is a tack on which the pointer K is pivoted. M is a ring attached to the inside of box B by means of a string and tack J¹. When set up ready for use as shown in Figs. 1 and 2, 65 A and B are held together at the back by means of the catch G which is hooked over the peg F. H is a pin on which the catch G is pivoted. When not in use the catch G is released from the peg F and the two boxes 70 are swung together on the hinges O, O and O inclosing the ring M and the animals E, E¹ and E².

The game is played by two or more persons as follows: One person turns the crank 75 C by means of the handle D¹ and crank D which moves the animals E, E¹ and E², and a second person attempts to lasso one of them by means of the ring M. The two end animals Q and Q¹ are larger than the center 80 animal Q² and five (5) points are scored when one of them is lassoed while ten (10) points are scored when Q² is lassoed as indicated by the figures above the animals. As shown the game is won by scoring fifty (50) 85 points in the least number of throws.

Figs. 3 and 4 show a modification in which the shaft C is rotated by means of a clock work which can be wound up and the game played without the necessity for one 90 person turning the crank.

In Figs. 3 and 4 A is the box, C the shaft having the cranks Q, Q¹ and Q². R is a gear fastened on shaft C and meshing with a gear S fastened on shaft Y. T is 95 another gear fastened on shaft Y and meshing with a gear W. Gear W is loosely mounted on shaft V. X is a spring fastened at one end to shaft V and at the other end to the gear W. U is a toothed wheel fastened to shaft W. U¹ is a pawl fastened to the box A by means of a pin U² for engaging with the toothed wheel U. The outer end of shaft V is square to accommodate D shown in Fig. 1. The clock work described 100 is wound up by placing the crank D on the squared end of shaft V turning it until the spring X is tightly coiled when the pawl U¹ holds the shaft V stationary. During 105 this winding the shaft C is kept from turn- 110

ing by holding one of the animals Q, Q¹ and Q². Upon releasing the animal held the shaft C revolves under the influence of the spring X until the spring X runs down.

5 Having thus described the invention what I claim as new is:

1. In a game, the combination of a box, a shaft having one or more cranks and mounted in said box, one or more slots in said box, 10 one or more animals attached to said cranks and projecting through said slots and means to revolve said shaft and thereby move said animals.
2. In a game, the combination of a box, a

shaft mounted in said box, a crank on said shaft, a slot in said box, an animal attached to said crank and projecting through and resting on the bottom of said slot, means to revolve said shaft and means to lasso said animal.

15
20

In testimony whereof, I have signed my name to this specification in the presence of two subscribing witnesses.

MICHAEL J. McINTYRE.
